UNITED STATES PATENT OFFICE

171,973

MILK CARTON HOLDER

Cecil L. Hays, Fort Worth, Tex.

Application August 20, 1953, Serial No. 26,523

Term of patent 3½ years

(Cl. D44—21)

To all whom it may concern:

Be it known that I, Cecil L. Hays, a citizen of the United States of America, residing at Fort Worth, in the county of Tarrant and State of Texas, have invented a new, original, and ornamental Design for a Milk Carton Holder, of which the following is a specification, reference being had to the accompanying drawing, forming a part thereof.

I claim:

The ornamental design for a milk carton holder, substantially as shown.
